G. F. STEELE, JR

LETTER BOX

Filed July 16, 1924

UNITED STATES PATENT OFFICE.

GROVE F. STEELE, JR., OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

LETTER BOX.

Application filed July 16, 1924. Serial No. 726,273.

My invention relates to the class of devices employed in connection with the delivery of mail matter by letter carriers, and an object of my invention, among others, is the provision of receptacles that shall be extremely convenient for the placing of mail matter therein by the letter carrier and from which the mail matter may be readily removed by the individual, such receptacles being especially adapted to receive mail matter of considerable length, such as magazines, and which may be secured against unauthorized extraction.

One form of box embodying my invention and in the construction and use of which the objects herein set out, as well as others, may be attained, is illustrated in the accompanying drawings, in which—

Figure 1 is a front view of a letter box embodying my invention, one of the doors for the removal of mail being shown as open.

Figure 2 is a similar view showing the mail delivery doors as open.

Figure 3 is a view in section on a plane denoted by the dotted line 3—3 of Figure 1.

It is common practice at the present time in the delivery of mail at residences and to individuals to provide receptacles to receive such mail, and certain rules are laid down by the Post Office Department to provide for ready distribution of the mail by letter carriers. It is also essential that the receptacles shall be so constructed as to receive all of the mail usually delivered by a letter carrier and to safeguard such mail from all unauthorized extraction. It is furthermore important that the mail deposited by the letter carrier may be easily and readily removed by the recipient. The invention illustrated and described herein provides such a mail box, in the accompanying drawings the numeral 5 indicating the body of the box that is preferably composed of a back, top, bottom and two sides. This is commonly formed from sheet metal in any desirable manner, and in many cases a number of these boxes are combined in a single structure, this being particularly convenient for use in apartment houses where many individuals are to be supplied with mail, and these boxes at the present time are com-

monly secured as in a recess 6 that is provided in the wall 7 of the building in which the box is located.

In order that mail may be secured against unauthorized removal the doors for gaining access to the receptacle are locked, and in the structure shown herein one door, to which the letter carrier may have a key, is provided for the insertion of mail and another door, to which the recipient has keys, is also provided with a lock. In order that the letter carrier may distribute his mail with a minimum loss of time, a lock for a plurality of doors is provided so that by unlocking this single lock the doors to the delivery openings to a plurality of boxes are released. As hereinbefore mentioned these delivery or service doors 8 are located at the upper end of the front of the mail box and they are each provided with a hinge 9 located preferably at the lower edge. A lock 10 is secured to both of the doors in any suitable manner, the bolt 11 of the lock being adapted to engage a keeper 12. By means of this construction the letter carrier by the use of a single key, releases all of the doors and opens them at once and after insertion of the mail matter the doors are both simultaneously closed and locked. While the illustration herein is with respect to two mail boxes having two doors, I contemplate an extension of the idea to structures containing more than two mail compartments and consequently having more than two doors, more than two of which may be controlled by a single lock and all of which may be simultaneously opened.

Doors 13 are provided for each of the compartments at the bottom thereof, said doors also being hinged at the bottom edge as at 14 and each of these doors may be provided with a lock 15 controlled by the person in possession of the receptacle containing this door.

Boxes of the kind contemplated hereby are commonly located in recesses in the walls of buildings, said recesses being made to receive said boxes, and the construction of the walls often imposes conditions such as to limit the thickness of the box to such a degree as to prevent the ready insertion and removal of mail matter of the longer

sorts, such as magazines, periodicals &c., such matter, if the box is limited in thickness to a degree imposed by the thickness of the walls of the building and not projecting unduly beyond the front face of such wall, making contact with the inner surface of the back of the box and the edge of the opening thereinto, this causing such matter to become wedged and requiring it to be bent or broken before it can be inserted in or taken out through an opening in the box. In order that such matter may be placed in the box through the upper door and may be as readily taken from the opening closed by the lower door, I have provided means embodying my invention, and illustrated and described herein, whereby receptacles of a thickness not undesirably greater than the depth of the recesses in which they may be contained are employed, the front of the box being so arranged that the longer pieces of mail matter, when deposited through the upper door will not be brought into close contact with the back of the box, and when removed through the lower door such matter will not be wedged between the lower opening and the back of the box.

In adapting my invention to overcome the objections hereinbefore noted I construct my improved box or receptacle of a minimum depth at such points that the longer pieces of mail matter will not be wedged as they are turned from the oblique position assumed when being placed in the box to a reversed oblique position when they are taken from the box. To accomplish this result I make the box or receptacle of a minimum width from front to back at about its lengthwise center and from this point it is flared outwardly on curved lines as at 17 and 18, towards the upper and lower ends of the front. From the edge of the portion 17 the door 8 comprising the upper portion of the front of the box slants backwardly to a point where it touches the top which is of a width from front to back substantially that of the minimum thickness of the box. The lower door 13 is formed on a curve extending from the upper edge of the opening closed thereby outwardly for a short distance and then inwardly to the point of attachment to the box, such bottom, the top and lengthwise central portions of the box being of a dimension from front to rear substantially that of the minimum width of the structure, and such box is, therefore, flush

at the top and bottom thereof with the front surface of the structure in which the recess 6 is formed, and the box may thus be located in a recess of minimum width without an undesirable projection therefrom.

It will thus be seen that the outwardly flaring portion 17 enables the longer pieces of mail matter to be inserted obliquely through the upper opening without undue contact with the back of the box until the lower end of such matter rests upon the bottom of the box at the back thereof, and the outwardly flared curved portion 18 enables such long pieces of mail matter to be grasped by a person reaching through the opening closed by the lower door to reverse the oblique positions thereof and to remove such matter through such opening without undue wedging by contact with the back of the box and the edge of the opening closed by the lower door.

In accordance with the provisions of the patent statutes I have described the principles of operation of my invention, together with the device which I now consider to represent the best embodiment thereof, but I desire to have it understood that the device shown is only illustrative and that the invention may be carried out by other means and applied to uses other than those above set out.

I claim—

1. A receptacle including a front wall with an opening therein for the passage of mail therethrough at one end of the receptacle, said wall sloping toward and to the boundary of said opening, and a second opening at the opposite end of said receptacle for the passage of mail, said sloping wall permitting the passage of mail in one direction through one of said openings and also the passage of said mail in the opposite direction through the other of said openings without wedging between the edges of the openings and the back of the receptacle.

2. A receptacle including a front located generally at substantially right angles to the top and bottom thereof, said front having an opening at the top and at the bottom thereof, and said front being curved and having a portion flaring outwardly toward each of said openings to permit the insertion and removal of long articles without wedging between the edges of said openings and back of the receptacle.

GROVE F. STEELE, JR.
